SAFETY AUTOMOBILE HEADLIGHT LENS

Edward L. Wood, Detroit, Mich.

Application June 17, 1949, Serial No. 3,376

Term of patent 14 years

(Cl. D48—32)

To all whom it may concern:

Be it known that I, Edward L. Wood, a citizen of the United States, residing at Detroit, in the county of Wayne and State of Michigan, have invented a new, original, and ornamental Design for a Safety Automobile Headlight Lens, of which the following is a specification, reference being had to the accompanying drawing, forming a part thereof, in which:

Fig. 1 is a front elevational view of a safety automobile headlight lens, showing my new design;

Fig. 2 is a side elevational view;

Fig. 3 is a bottom elevational view; and

Fig. 4 is a rear elevational view.

I claim:

The ornamental design for a safety automobile headlight lens, substantially as shown.

EDWARD L. WOOD.
